Hans Hogeman, Longmeadow, Mass., assignor to American Bosch Arma Corporation, a corporation of New York

Filed Apr. 21, 1961, Ser. No. 64,887

Term of patent 14 years

(Cl. D65—1)

Fig. 1.

Fig. 2.

Fig. 3.

FIG. 1 is a perspective view of a housing for a fuel injection pump embodying my new design;

FIG. 2 is an elevational view thereof from the right side as seen in FIG. 1; and

FIG. 3 is a top plan view thereof.

The undisclosed side of the housing for fuel injection pump is substantially the same as is the side shown to the left of the perspective view of FIG. 1.

The dominant features of the design are shown in full lines in the drawings.

I claim:

The ornamental design for a housing for a fuel injection pump, substantially as shown and described.
